JACK

Richard L. Foringer, Syracuse, N. Y.

Application April 18, 1941, Serial No. 389,187

5 Claims. (Cl. 280—34)

The invention relates to a jack suitable to be used to raise a tank, other circular body, or a body having inclined sides which is resting on the floor or upon narrow cleats, whereupon the tank or the like may be pulled away. The jack utilizes the inclined sides of the circumference of the tank or the curve of the body to lift the same. A square tank may rest on cleats having inclined faces, or other means may be provided therefor. A jack may be provided at each end of a tank to completely lift the same from the floor so that it may be pulled to any desired place.

It is an object of the invention to construct a jack which is simple in construction and consequently inexpensive to manufacture and yet is effective to raise heavy bodies.

Another object of the invention is to provide spaced means which are pulled together linearly until they engage the inclined surface of the tank or other body and raise the latter, the spaced means being pulled together by operating means having the double function of supporting the spaced means in their spaced relation and drawing the spaced means linearly and horizontally towards each other to raise the body so that a separate frame is eliminated.

Another object of the invention is to construct a jack of the type having a pair of spaced means, which are drawn towards each other to raise the body so that the operating means is necessarily spaced from the supporting axis of the spaced means, and having a pair of operating screws forming the operating means to offset the tendency of the spaced means to angularly spread when the weight of the body is placed thereupon.

Other objects of the invention will be more apparent from the following description taken in connection with the accompanying drawings, illustrating two embodiments of the invention, in which:

Figure 1 is a side elevational view of one form of jack in position at the end of a tank ready to have the spaced means drawn together so that the end of the tank can be raised off of the floor.

Figure 2 is a view showing the end of the tank raised by the jack.

Figure 3 is a plan view of the jack.

Figure 4 is an end view of the jack and the end of a tank raised thereby.

Figure 5 is a plan view of another form of jack having a pair of operating screws.

Figure 6 is a section of the jack of Figure 5, 55

taken on line 6—6 of and projected from that figure.

Figure 7 is a diagrammatic view of the jack and the end of a tank showing the forces applied upon the jack by the weight of the tank.

Figure 8 is a diagrammatic view of the end of a tank and the jack of Figure 5 showing the application, by the use of arrows, of forces thereon in a horizontal plane.

10 The two forms of jack illustrated are substantially alike in that both use spaced means which are drawn together to engage and raise the end of a tank. Also the operating means or screws for drawing the spaced means together serve also as the frame for holding the spaced means in spaced relation without the use of an independent frame.

The jack of Figure 1 includes a pair of spaced means or frames 10, 11, each of which preferably has a pair of spaced tank engaging rollers 12 which engage the tank or body to be raised. Any suitable body engaging means may be provided in place of the rollers 12 illustrated. Roller means, which is preferably a caster 13, is secured to each frame 10, 11 so that the vertical axis of the caster is between the tank engaging rollers 12. Greatest stability is obtained if the vertical axis is midway between the outer ends of the rollers. A line lying in an imaginary plane extending through the vertical axes of the casters 13 may be defined as the supporting axis of the jack.

Operating means is provided in the screws 16 and 17 and tubular nut 18. The screw 16 is carried by the frame 10, the screw 17 is carried by the frame 11, and the elongated nut 18 couples the two screws together. The screw 16 is provided with a thread in one direction, such as a left-hand thread, and the screw 17 is provided with an opposite or right-hand thread. Upon rotation of the tubular nut 18, the pair of spaced means is drawn toward each other, whereupon the tank or body engaging rollers 12 engage the circular surface of the tank, and upon further movement toward each other, the tank is raised off of the floor. It will be observed, therefore, that the operating means not only serves to draw the spaced means towards or away from each other, but also provides the frame for supporting the spaced means in spaced relation, so that a separate frame may be dispensed with. It is for this reason that the operating means is spaced from the supporting axis of the spaced means and is parallel therewith.

Any suitable means may be utilized to rotate

the tubular nut 18; ratchet means, however, is the preferred construction. The ratchet means includes a ratchet wheel 20 which is secured to the tubular nut 18 in any suitable manner. A pawl 21 is carried upon a pivot 22 which is secured in the arms of a fork 23, the fork being freely mounted upon the tubular member 18 so that it may rotate thereupon. The pawl 23 is double ended so that one end thereof may engage the ratchet wheel 20 to rotate the tubular nut 18 in one direction to draw the spaced means together and raise the body to be lifted or moved, and then when it is desired to lower the same to the floor, the pawl is shifted so that its other end engages the ratchet wheel 20 in order to rotate the ratchet wheel and tubular nut 18 in the opposite direction which moves the spaced means away from each other.

Preferably the fork 23 has a handle 25 extending therefrom, which handle may be pivoted to the fork by means of a pivot pin 26. The pivot pin renders it easier to pull the tank in any direction when it is resting on a jack or jacks.

With a single screw operating means as illustrated in Figures 1 through 4, which necessarily is parallel to but spaced from the supporting axis of the spaced means, as previously discussed, when the weight of the tank T or body is placed upon the spaced means, there is a tendency to separate the spaced means angularly away from each other, that is, to cock them relatively to the nut, such as the tubular nut 18. This may be obviated by making the nut relatively long so that it has a long engagement with the operating screw, or it may be obviated by using a double operating screw, as illustrated in Figures 5 through 8. In this construction the spaced means again includes a pair of spaced frames 30 and 31 which are provided with means for engaging the tank or body to be raised, which preferably is a pair of spaced tank engaging rollers 32. Each frame carries as a part of the spaced means a roller means 33 which engages the floor. The roller means preferably are casters, and again stability is obtained if the vertical axis of each caster is midway between its respective tank engaging rollers 32. Here, again, a line lying in an imaginary plane extended through the vertical axes of the casters constitutes the supporting axis.

The jack of Figures 5 through 8 is also provided with operating means which not only serves to draw together or separate the spaced means so that a tank may be raised from the floor or lowered to the floor, but also serves as the frame for supporting the spaced means in spaced relation. This operating means, in the construction particularly illustrated, also constitutes screw means which is spaced from and parallel to the supporting axis of the jack. The operating means comprises a pair of parallel screws 34 and 35. One end of the screw 34 has a thread of one direction, such as a right-hand thread, and the other end has a thread of the other kind, such as a left-hand thread. The screw 35 similarly has a different kind of thread at each end thereof, and in addition thereto, corresponding or adjacent ends of the screws 34 and 35 are threads of opposite kind, that is, if the left-hand end of the screw 34, as shown in Figure 5, has a right-hand thread, then the left-hand end of the screw 35 carries a left-hand thread. In other words, the ends of each screw carry an opposite thread and adjacent ends of the pair of screws are also opposite. One end of each screw is threadedly re-

ceived in the frame 30 and the other end of each screw is threadedly received in the frame 31, so that each frame provides its own nut for each screw.

5 Any suitable means is provided for rotating the screws, ratchet means, however, being preferred. The ratchet means includes a ratchet wheel 38 which is secured or keyed to the screw 35. A pawl 39 is carried upon a pin 40 which is in turn carried by a fork 41. The fork is freely mounted upon the screw 35 to oscillate thereupon. The pawl 39 is of the double ended type so that one end of the pawl may engage the ratchet wheel 38 for rotating the same and the screw 35 in one direction, or when it is desired to rotate the screw 35 in the opposite direction, the other end of the pawl is brought into engagement with the ratchet wheel. The spring 42 retains either end of the double pawl in contact with the ratchet wheel.

The ratchet wheel 38 also preferably serves as a gear which meshes with a gear 45 secured or fixed upon the operating screw 34 in any suitable manner, such as by keying. The straps 46 retain the gear 45 in mesh with the gear or ratchet wheel 38 and prevent axial displacement thereof along the screw 34.

Since the gears 38 and 45 rotate in opposite directions, thereby rotating the screws 34 and 35 in opposite directions, the threads at corresponding ends of the screws must be of opposite kind. The spaced operating screws 34 and 35 overcome the tendency of the spaced frames 30 and 31 to angularly separate from each other when the weight of the tank is placed thereupon. This angular displacement could similarly be rectified with a single screw by providing a relatively long bearing or nut surface upon the respective frames 30 and 31.

30 40 In both constructions of jack, roller or rollers 32 are essential where the jack is to be used first to raise a tank or other body off the floor and then rotate the same on the jack rollers 32 for any purpose, such as welding or riveting the tank plates. The jacks described herein are well suited for this purpose since the tank or body is first raised off of the floor on the rollers and is then supported thereon so that it can be rotated at will, as the work progresses, to bring the welding or riveting point to any desired or convenient level or position for the workman.

50 45 The ends 48 of the operating screws 34 and 35 may be squared to receive a wrench 49 for initial rapid movement of the spaced frames towards or away from each other. A wheel or preferably a caster 50 may be provided below the ratchet mechanism, if desired, which improves the stability of the jack. Where such additional caster is used, it is not necessary for the vertical axis of each caster 33 to be located between the ends of the rollers 32, but each may be shifted towards the end of the frame if desired.

60 55 This invention is presented to fill a need for improvements in a jack. Various modifications in structure, as well as changes in mode of operation, assembly, and manner of use, may and often do occur to those skilled in the art, especially after benefiting from the teachings herein. Hence, it will be understood that this disclosure is illustrative of preferred means of embodying the invention in useful form by explaining the construction, operation and advantages thereof.

What is claimed is:

70 75 1. A jack comprising a pair of spaced frames, means carried by each frame to engage the body

to be raised, roller means carried by each spaced frame and engaging the floor, a pair of spaced screws parallel with and spaced from the supporting axis of the frames and threadedly engaging the frames in spaced relation to support the same, said screw means also being operative to draw at least one of the frames horizontally and linearly towards the other, ratchet means operatively connected with the screws, and a handle connected with the ratchet means to operate the same. 10

2. A jack comprising a pair of spaced frames; means carried by each frame to engage the body to be raised; roller means carried by each spaced frame and engaging the floor; a pair of spaced screws parallel with and spaced from the supporting axis of the frames and threadedly engaging the frames in spaced relation to support the same, said screw means also being operative to draw at least one of the frames horizontally and linearly towards the other; operating means connected with the screws including a ratchet frame, a ratchet means, and a handle connected with the ratchet means to operate the same; and a roller means carried by the ratchet frame. 15

3. A jack comprising a pair of spaced frames, means carried by each frame to engage the body to be raised, roller means carried by each spaced frame and engaging the floor, a pair of spaced screws parallel with and spaced from the supporting axis of the frames and each end of each screw threadedly engaging each frame in spaced relation to support the same, said screw means being operative to draw at least one of the frames horizontally towards the other, a gear operative- 20 35

ly connected with each screw and meshing with each other, a pawl operatively engaging one of the gears, and a handle connected with the pawl to oscillate the same and rotate the gears and screw means simultaneously. 5

4. A jack comprising a pair of spaced frames, spaced roller means carried by each frame in alignment to engage the body to be raised, roller means engaging the floor and carried by each spaced frame, screw means parallel with and spaced from the supporting axis of the frames, and supporting the frames in spaced relation, said screw means being operative to draw at least one of the frames horizontally towards the other, ratchet means operatively connected with the screw means to rotate the same, means for manually operating the ratchet means, and additional selective means for operating the screw means independently of the ratchet means. 10

5. A jack comprising a pair of spaced frames, spaced roller means carried by each frame in alignment to engage the body to be raised, roller means engaging the floor and carried by each spaced frame, screw means parallel with and spaced from the supporting axis of the frames, and supporting the frames in spaced relation, said screw means being operative to draw at least one of the frames horizontally towards the other, ratchet means mounted on the screw means between the spaced frames and operatively connected with the screw means to rotate the same, and means for manually operating the ratchet means. 25 30

RICHARD L. FORINGER.
